United States Patent Office

Des. 178,437
Patented July 31, 1956

178,437

LETTER OPENER

Horace L. Walborn, Jackson, Mich., assignor to Walmann Products, Battle Creek, Mich., a firm

Application January 19, 1955, Serial No. 34,056

Term of patent 14 years

(Cl. D74—1)

— F 1 —

— F 2 —

I claim:

The ornamental design for a letter opener, substantially as shown and described.
